CLAIM

The ornamental design for a floodlight, as shown and described.

DESCRIPTION

FIG. 1 is a perspective view of a floodlight showing my new design;

FIG. 2 is a front elevation view thereof;

FIG. 3 is a back elevation view thereof;

FIG. 4 is a bottom planar view thereof;

FIG. 5 is a top planar view thereof;

FIG. 6 is a right side view thereof; and,

FIG. 7 is a left side view thereof.

The broken lines depict environment that forms no part of the claimed design.
